NOAH H. ROBINSON, JOHN C. BROWNING, AND LEWIS A. SMITH, OF QUAKER, WEST VIRGINIA

GAS AND WATER SEPARATOR

Application filed May 10, 1928. Serial No. 276,696.

In the natural gas field, it frequently happens that the gas coming from the well carries with it a considerable volume of water and this water tends to obstruct the flow of gas in the mains and also interferes with its successful use. It is the object of our invention to provide a simple inexpensive and efficient mechanism which may be placed in a gas line and will operate automatically to remove from the gas the water which may be carried by the same. The invention also has for its object the provision of means whereby the water may be discharged from the separating mechanism, and a further object is to provide an arrangement whereby the working parts may be easily removed from the casing of the separator whenever inspection or repair of the same is deemed desirable. Other objects of the invention will appear incidentally in the course of the following description, and the invention resides in certain novel features which will be particularly pointed out in the appended claim.

In the accompanying drawing:

Figure 1 is a longitudinal section of a separator embodying the invention;

Fig. 2 is a transverse section on the line 2—2 of Fig. 1, and

Fig. 3 is an enlarged detail section of the float-controlled valve.

In carrying out the invention, there is provided a casing 1 which may be constructed of wrought metal or be a casting and which is illustrated as rectangular but may be of any other approved form. Through one side of the casing is an opening 2 and this opening is covered by a plate 3 which is rigidly bolted to the side of the casing and upon which all of the working parts are mounted and carried. Suitable packing is, of course, provided between the edges of the plate 3 and the side of the casing so as to prevent leakage, and in the bottom of the casing is a depression or well 4, the purpose of which will presently appear. At the ends of the casing at the top of the same are offsets 5 from which nipples 6 extend to be coupled into the gas line or main, portions of which are indicated at 7, it being understood that the nipples 50 may be connected to the main by any ap-

proved form of coupling which will be sufficiently leak-proof and easily secured. Depending from the top of the casing adjacent each offset 5 is a baffle plate 8 which depends to a point below the horizontal plane of the axis of the gas main and the nipple 6 so that the mingled gas and water entering the casing will be turned downwardly to permit the water to collect in the casing while the gas may continue to flow through the casing. It will be noted that a baffle is provided adjacent each end of the casing so that no particular care is needed when assembling the casing with the sections of the gas main inasmuch as either end of the casing may be presented toward the source of flow.

Secured upon the inner side of the cover or plate 3 at a convenient point in the height of the same is a post or bracket 9 which is provided at its inner end with an eye or collar 10 through which a vertical pipe 11 passes. The upper end of the pipe 11 is connected by an elbow 12 to a short pipe 13 which extends through the cover to discharge outside the casing. The pipe 11 extends nearly the full height of the casing and near its lower end is equipped with a T-coupling 16 from which a branch pipe 17 extends through the cover 3 to discharge outside the casing in the same manner as the pipe 13. If desired, the discharge pipes may be extended to some remote point. The lower extremity of the pipe 11 is threaded into a valve casing 22 which flares downwardly and is formed, intermediate its ends, with a partition 23 constituting a seat for a needle valve 24. The valve 24 is pivotally attached at its lower end to a lever 25 which is pivoted at one end to the lower end of a connecting rod 26 which has its upper end pivoted to a fork 27 on one end of a float lever 28, a float 29 being carried by the opposite end of said lever. The float lever is fulcrumed at the fork 27 upon a collar 30 which is secured upon the pipe 11, said pipe, consequently, serving as a post to support the working elements. The end of the lever 25 remote from the connecting rod 26 is pivoted to the lower end of a link 31 which depends from and is pivoted to an arm 32 preferably formed integral with the valve casing 22, 100

and a brace 33 extends from the outer end of said arm 32 and the lower outlet pipe 17 to impart rigidity to the structure supporting the needle valve and the means for actuating the same.

Initially, the casing will be empty and the float 29 will be in its lowest position, as shown in the drawing. When gas flow is established through the upper portion of the casing, the 10 water carried by the gas will be deflected to the bottom of the casing and will accumulate therein, as has been stated. As the level of the water rises, the float, of course, will be caused to swing upwardly and eventually the 15 movement of the float will be transmitted through the float lever and the connected parts to swing the valve lever 25 downwardly and unseat the valve 24. As the level of the water in the casing rises, the gas in the top of the 20 casing will be put under increasing pressure and will, in turn, react upon the water so as to force the same through the valve casing 22 past the valve seat and into the pipe 11. A siphonic action through the pipe 11 will be 25 thereby set up so that the water will all be caused to flow from the casing and restore the normal conditions. As the water is discharged, the float, of course, will descend and eventually the valve will be again seated. 30 It is obvious that if the cover 3 be removed all of the working parts will be likewise removed so that access to the operating elements is easily had. The depression or well 4 in the bottom of the casing accommodates 35 the valve lever 25 and the parts connected therewith so that the valve may be arranged at a very low point in the casing and all of the water permitted to discharge. It is to be understood that the proportion of the parts 40 is such that the valve will not be completely unseated until the float has reached a high point in the casing and it will remain unseated until the float is practically at the lowest point of its movement. The apparatus 45 is very simple and may be installed at a very low cost. The water eliminated from the gas may be discharged in any manner most convenient under any given circumstances and if the main is exposed so that 50 freezing is apt to occur the casing may be buried below the frost line, the main being, of course, correspondingly bent so that whatever the location of the casing 1, the gas flowing from the well must enter and pass 55 through the casing in order to reach the storage tanks or points of use. It sometimes happens that the gas pressure is relatively low and the moisture content is excessive so that the lower outlet 17 will not carry off the 60 water as rapidly as desired, the upper outlet 13 then coming into use. By having a long upright pipe of small diameter, a high siphonic action is attained so that all the water, except the very small portion which collects 65 in the well 4, will be withdrawn.

Having thus described the invention, we claim:

A separator of the class described comprising a casing having an inlet for gas and water at one end and an outlet for gas at the opposite end, a water outlet pipe secured within the casing with one end at the bottom thereof, branch pipes leading from said water outlet pipe through a side of the casing, a valve casing secured on the lower end of said water outlet pipe and flared downwardly, a needle valve arranged to seat upwardly within the valve casing, an arm projecting laterally from the valve casing, a link depending from said arm, a lever pivoted to said link and extending across and pivoted to the lower end of the valve, a float lever fulcrumed on the water outlet pipe above the valve casing, and a link connecting one end of the float lever with the corresponding end of the valve lever.

In testimony whereof we affix our signatures.

NOAH H. ROBINSON. [L. S.]
